R. LILLIE

FUEL FEEDING DEVICE

Filed April 25, 1921

Patented Apr. 27, 1926.

1,582,834

UNITED STATES PATENT OFFICE.

RAY LILLIE, OF CHICAGO, ILLINOIS, ASSIGNOR OF ONE-HALF TO THE INVINCIBLE BLOW PIPE CO., OF CHICAGO, ILLINOIS, A CORPORATION OF ILLINOIS.

FUEL-FEEDING DEVICE.

Application filed April 25, 1921. Serial No. 464,302.

To all whom it may concern:

Be it known that I, RAY LILLIE, a citizen of the United States, residing at Chicago, in the county of Cook and State of Illinois, have invented certain new and useful Improvements in Fuel-Feeding Devices, of which the following is a specification.

This invention relates to improvements in fuel feeding devices.

10 An object of the invention is to automatically control fuel conveyed to furnaces of a boiler by variation of steam pressure therein, to thereby maintain substantially constant pressure.

15 Another object is to automatically control fuel conveyed to the furnace of a boiler and coincidentally to control the air required to aid combustion of the fuel fed to the boiler, the feeding of air and fuel being controlled by variation of pressure in the boiler.

20 Other, further, and more specific objects of the invention will become readily apparent, to persons skilled in the art, from a consideration of the following description 25 when taken in conjunction with the drawings, wherein:—

Fig. 1 shows in side elevation a schematic arrangement of the several devices for the purpose of carrying my invention into effect.

20 Fig. 2 shows a front elevation of a furnace with the invention applied thereto, parts being broken away.

Fig. 3 shows an enlarged end view of the conveyor, and the operating mechanism therefor.

35 Fig. 4 is a section thru the diaphragm device which is responsive to pressure.

In all the views the same reference characters are employed to indicate similar parts.

40 In the structure chosen to disclose the invention 5 represents a boiler, 6 the furnace door therefor, and 7 is the ash door. 8 represents the boiler setting.

45 A fuel conveyor 9' is rotatable by any suitable means in a pipe 10. The shaft 9 of the conveyor 9' has a bearing in the closed end 11 of the pipe and projects therebeyond. A pipe 12 is connected to the pipe 10 and leads downwardly to the bottom of the furnace door 6. Shavings and other débris about a factory may thus be conveyed from remote points by the operation of the conveyor 9', thru the pipe 12, into the furnace. In order that combustion may properly be promoted I provide a fan 13 driven by an

electric motor 14 and having a pipe 15 communicating with a nozzle 16 which opens into the fire box through the bottom of the door 6, as at 17, so that air is thereby forced into the furnace under the bottom of the incoming fuel which passes thereinto thru the pipe 12. The electric motor 14 also drives a speed reducing device 18, which, in the particular illustration, consists of a worm and worm wheel, not shown, but enclosed within the casing and having a shaft 19 to which a crank pin 20 is connected.

An arm 21 is oscillatable upon the outer end of the shaft 9 and is connected by a link 22 to the crank pin 20. When the shaft 19 is rotated the arm 21, which is pivotally supported on the shaft 9, is oscillated. The arm 21 carries a pawl 23 held against the teeth of a ratchet wheel 24 by a spring 25. The wheel 24 is fixed to the conveyor shaft 9 so that when the arm 21 is oscillated the pawl 23 will engage the teeth on the wheel 24 and intermittently rotate the shaft and therewith the conveyor 9'. Another arm 26 is pivoted on the shaft 9 outside of the wheel 24 and this arm 26 carries a curved shield 27, which may be interposed between the wheel 24 and the pawl 23 to lift the pawl from the wheel, and to prevent the pawl from having contact with the wheel during part of its entire stroke.

50 The arm 26 is connected by a link 28 to the arm 29 of the bell crank that is pivoted at 30. The other arm 31, of the bell crank, is pivoted to a vertical rod 32, and this rod is connected to a pressure responsive diaphragm 33 inside of the casing 34.

The casing 34 is connected by a pipe 35 to the steam space in the boiler with which the device is associated. The arm 26 is also connected by a link 36 to a flap valve 37 which is pivoted, as at 38, and which will close an opening 39 in the air pipe 40, when the flap is in proper position. The operation of the device is as follows:

55 The arm 21 is oscillated a given uniform distance by a revolution of the crank pin 20 on the shaft 19 at each revolution of the shaft. As the arm 21 is moved to the right the pawl 23 will engage the teeth on the wheel 24 and if not prevented will move the wheel 24 the full excursion of oscillation of the arm 21, but the shield 27 may be interposed between the pawl 23 and the wheel 24 and thereby prevent the pawl from

engaging the teeth of wheel 24 until the pawl rides off the end of the shield. The position of the shield 27 is determined by the pressure in the boiler. When the pressure is high the arm 31 of the bell crank is raised and the link 28, which is connected to the arm 26, is moved outwardly of the boiler, thereby causing the shield 27 to be introduced between the pawl 23 and the wheel 24 giving the pawl a shorter operative stroke and causing the conveyor 9' to be rotated accordingly.

It is, of course, manifest that the slower the speed of the conveyor the less amount of fuel it will move in a given time and that the position of the shield controls the extent of movement of the conveyor at each oscillation of the arm 26 in response to variations of steam pressure of the boiler.

As the steam pressure rises above a predetermined point a smaller quantity of fuel is therefore fed into the boiler, in the manner heretofore described, and less air is passed into the furnace because the flap 37 is opened by the same movement of the arm 26 that shortens the effective stroke of the pawl. When the steam goes down the diaphragm 33 will go down and cause the arm 31 to be depressed and produce a rearward movement of the arm 29 of the bell crank, thereby moving back to its original position the oscillating arm 26 which has the effect to retract the shield 27 giving the pawl a longer stroke, and causing more fuel to be fed into the boiler at a given time; at the same time the flap valve 37 is closed causing a full quantity of air to be passed thru the pipe 15 into the boiler, and therefore the quantity of air is allowed to be forced into the furnace or boiler to support combustion of

the fuel fed therein by the means heretofore described.

Having described my invention what I claim as new and desire to secure by Letters Patent, is:—

1. An apparatus for feeding fuel to a boiler furnace to maintain substantially constant pressure in the boiler comprising a fuel conveyor, a pipe connecting the conveyor and furnace and through which the fuel is moved by effect of gravity, means to intermittently move the conveyor, substantially constant speed air compressing means, a conduit leading directly from said air compressing means to said furnace terminating below said pipe, means responsive to the pressure in the boiler, arranged coincidently to control the movement of the conveyor and to vary the air supply as the fuel and air are fed to the furnace. 45

2. A device of the character described comprising a fuel conveyor, a furnace, a pipe leading from the conveyor to the furnace through which fuel is moved by the effect of gravity, an air fan driven at substantially constant speed, a pipe leading from the fan directly to the furnace, means to actuate the conveyor operable by the fan driving mechanism, a boiler, a valve in the air pipe, a device responsive to pressure in the boiler and arranged simultaneously to control the extent of movement of the conveyor by said actuating means and the extent of opening of said air valve to vary coordinately the fuel and the air supplied to the 50 boiler. 65

In testimony whereof I hereunto subscribed my name.

RAY LILLIE.
